UNITED STATES PATENT OFFICE

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS

STACK CONTROL DEVICE FOR OIL BURNER SYSTEMS

Application filed December 21, 1925. Serial No. 76,581.

This invention relates to improvements in electric control devices particularly adapted for use in liquid fuel burning systems and more particularly to what is termed in the 5 trade as a stack control device for oil burning systems. While the embodiment of this invention is illustrated and described in this application as a stack control, yet, it is to be understood that other embodiments may be 10 constructed for other installations for the purpose of controlling an electric circuit actuated by a rise and fall in temperature without departing from the scope of this invention.

It is an object of this invention to provide 15 a device adapted to be installed upon the stack or pipe leading from an oil burning furnace to the chimney or smoke stack which will control an electric circuit transmitting electric energy to operate a motor actuated 20 oil burner by the rise and fall of the temperature within said stack. It is also an object of this invention to provide a device of this character with a thermal element entering within the interior of the stack and effected 25 by the temperature therein to expand and contract and upon expansion or contraction to positively throw an electric switch to close or open an electric circuit therethrough. It is a still further object of this invention to 30 provide a device of this character which upon the initial expansion or contraction of the thermal element will immediately operate to throw the switch to one position or the other and will allow further contraction or expansion of the thermal element without effecting the position of the switch, but which will immediately upon a reversal of the movement of the thermal element instantly throw the switch to the opposite position.

While a preferred form of this invention is illustrated upon the accompanying sheets of drawing yet it is to be understood that minor detail changes may be made therein 45 without departing from the scope of this invention.

Figure 1 is a view in side elevation of an embodiment of this invention, with parts broken away and partly in section.

50 Figure 2 is a view in front elevation of the

instrument casing with the cover removed and showing the parts in neutral position.

Figure 3 is a view similar to Figure 2 illustrating the position of the switch when thrown into open position.

Figure 4 is a view similar to Figure 2 showing the position assumed when the switch is thrown into closed position.

Figures 5 and 6 are views similar to 3 and 4 of a modified form of this invention.

This device is adapted to be attached to the stack or pipe leading from an electrically operated oil burner furnace or heater connecting the fire box or fire pot of such heater to the conventional chimney or smoke stack which is indicated by the dot and dash lines of Figure 1. The casing 1 which contains the switch mechanism is provided with a removable cover 2 and is secured to the stack by providing an opening therein of sufficient size to receive the sleeve 3 provided with a flange adapted to be secured to the exterior of the rear of the casing 1. The sleeve 3 is passed through the opening provided in the stack and is secured thereto by the adjustable sleeve 4 mounted thereon being brought into engagement with the interior of the stack and secured in such a position by a set screw. The sleeve 3 is provided with a central bore and the rear of the casing is provided with an opening of similar size in line therewith. A shouldered shaft 5 is rotatably mounted within the bore of the sleeve 3 and extends within the interior of the casing 1 at one end, with the enlarged portion having its shoulder 55 in engagement with the interior of the sleeve 3, which enlarged portion projects into the interior of the stack and is preferably provided at its inner end with an enlarged cylindrical head having a transverse slot 6 therethrough. A spiral coil 7 of thermal material, preferably formed of a bi-metal strip, is secured at one end in the slot 6 by a set screw, as shown, and at the other end to the sleeve 3, so that as the temperature in the 60 stack increases or decreases the thermal element will expand or contract and impart a rotation in one direction or the other to the shaft 6. Upon the end of the shaft extending into the casing 1 a hub 8 is secured, as shown,

65 70 75 80 85 90 95 100

which hub is provided with a toothed wheel 9, the teeth 10 of which are preferably of the knife-edged type and may extend entirely around the wheel or only about the lower portion thereof under certain conditions.

A mercury tube switch 11 of commercial form is carried in a clip 12 mounted upon a pivoted member 13 mounted to rotate upon a block 14 secured to the rear of the casing 1 10 and at such a distance therefrom that the upper contracted portion thereof 15, which is preferably formed to terminate in a knife-edge, will be engaged by the teeth 10 of the toothed wheel 9. Counterweights 16 and 17 15 are preferably secured on opposite sides of the member 13 below its pivot 18 to normally maintain the member in a vertical position with its upper knife-edge normally entering between two of the teeth 10 of the toothed 20 wheel 9 and in this position support the mercury tube switch 11 in a horizontal or neutral position whereby the mercury within the tube is out of contact with the terminals of the switch. As additional means for normally causing the pivoted member to assume 25 this vertical position shown and to return the pivoted member to this position, flat compression springs 19 and 20 are secured to opposite sides of the casing 1 with their free 30 ends slidably engaging the counterweights 16 and 17, as shown in Figure 2.

In the type of mercury tube switch shown, the two terminals thereof are spaced apart and introduced at one end of the tube so that 35 when the tube is tilted in the direction shown in Figure 3 the mercury will accumulate in the lower end away from the terminals and when tilted into the position shown in Figure 4 the mercury will accumulate in the other 40 end to engage and close the circuit between the two terminals. The terminals are connected by flexible leads 21 and 22 to binding posts or other electrical connections through which the electric circuit to be controlled 45 passes.

In the embodiment of this invention illustrated, the parts are so arranged as to normally assume the position shown in Figure 2 and upon an increase in temperature to a 50 predetermined degree in the stack, the thermal element in expanding will rotate the toothed wheel to throw the pivoted arm into the position shown in Figure 4, whereby the circuit is closed through the mercury tube switch 11. This action will take place immediately upon the expansion of the thermal element 7 causing the rotation of the shaft 5 and a knife-edged tooth of the wheel to be 55 immediately brought into engagement with the knife-edged termination of the pivoted member 13 which will overcome the counterweights upon such member and the tension of the spring 20 to turn it about its pivot. A further expansion of the thermal element 7 60 causing a further rotation of the shaft 5 will

cause the teeth 9 to wipe over the knife edge 15 of the pivoted member without imparting further movement thereto, but at the same time holding said member against its normal tendency to return to the vertical and a tooth of the wheel 9 will always be in engagement with the knife edge 15 against such tendency so that as soon as the thermal element 7 begins to contract from whatever degree it may have been raised, the toothed wheel will be 75 caused to rotate in the opposite direction bringing the adjacent tooth thereof in contact with the opposite side of the knife edge 15 and tilt the pivoted member toward the vertical position, and as soon as the movement of contraction of the thermal element 7 begins the counterweights 16 and 17 and the spring 20 will initiate a return of the pivoted member 13 to the vertical thereby causing the mercury in the tube 11 to flow away 85 from the contacts of the switch to break the circuit therethrough, and upon further contraction, a further movement in the same direction will be imparted to the toothed wheel 9 causing the pivoted member 13 to be rotated 90 about its pivot until it assumes the position shown in Figure 3, and further rotation of the toothed wheel in the same direction will cause the teeth thereof to wipe over the knife edge 15 of the pivoted member 13. After the 95 thermal element 7 has contracted to normal or with the parts in the position shown in Figure 3, a predetermined increase in temperature will cause an expansion of said member to rotate the shaft and toothed wheel in 100 the opposite direction acting upon the pivoted member 13 in the manner first described which will close the circuit through the terminals of the electric switch 11. The engagement between the pointed end 15 of the pivoted member 13 and the teeth 10 of the wheel 9 is a positive one and is in effect a pawl and ratchet movement. There is a positive interlocking or engagement between the toothed wheel and pivoted member which 105 will impart upon rotation of the wheel an instantaneous positive tilting of the mercury tube switch to open or close the circuit there-through.

In the modification shown in Figures 5 and 6, the operation is the same as herein-before described, the difference being in the specific means for returning the pivoted member to the normal or vertical position. In this type the counterweight 30 upon the pivoted member 13 is smaller than that shown in the first four figures and in place of the springs 19 and 20, pivoted bell crank levers 31 and 32 are substituted. These levers are pivoted at their apexes on either side of the vertical central line of the pivoted member 13 with one arm of each arranged parallel thereto terminating in curved noses 33 and 34 adapted to engage the sides of the pivoted member 13 when in its normal vertical posi- 115 120 125 130 135

tion. The other arms each support a counterweight 35 upon their outer extremities and are normally supported in horizontal position by stops 36 and 37 extending thereunder from the back of the casing 1. When a movement of the toothed wheel 9 causes the pivoted member to move into the extreme open position, as shown in Figure 5, the left bell crank lever 31 will be rotated about its pivot so that its counterweight 35 acts in the same manner as the spring 19 to return the pivoted member 13 to the vertical position as soon as the toothed wheel initiates a rotation in the opposite direction, while the other bell 15 crank lever 32 remains inactive as it is supported in the horizontal position by the stop 30. When the toothed wheel 9 rotates in a direction to close the circuit, as shown in Figure 6, the bell crank lever 31 remains supported upon the stop 36 while the bell crank lever 32 is rotated about its pivot against its counterweight 35 and, in the position shown in Figure 6, exerts a pressure to urge the pivot member 13 back to its vertical position.

25 What I claim is:

1. In a thermostatic controlled electric switch, a rotatable operating element, a thermal element adapted upon expansion and contraction to rotate the operating element, in opposite directions, a pivoted member, an electric circuit closer mounted upon said member, a plurality of engaging members mounted on the operating element adapted to engage one end of the pivoted circuit closer carrying member and upon rotation of the operating element to turn it about its pivot to open or close the circuit through the circuit closer and upon further rotation in the same direction, to move out of engagement but 40 maintain the circuit closure in the same position.

2. In a thermostatic controlled electric switch, a rotatable operating element, a thermal element adapted upon expansion and contraction to rotate the operating element in opposite directions, a pivoted member, an electric circuit closer mounted upon said member, a plurality of engaging members mounted on the operating element adapted 45 to engage one of such members with one end of the pivoted circuit closer carrying member and upon rotation of the operating element to turn it about its pivot to open or close the circuit through the circuit closer, and upon further rotation in the same direction to move such member out of engagement but maintain the circuit closer in the same position.

3. In a thermostatic controlled electric switch, a rotatable operating element, a thermal element adapted upon expansion and contraction to rotate the operating element in opposite directions, a pivoted member, an electric circuit closer mounted upon said member, a plurality of engaging members

mounted on the operating element adapted to engage one of such members with one end of the pivoted circuit closer carrying member and upon rotation of the operating element to turn it about its pivot to open or close the circuit through the circuit closer, and upon further rotation in the same direction to move such member out of engagement but maintain the circuit closer in the same position, by the engagement of the next adjacent 75 engaging member.

4. In a thermostatic controlled electric switch, a rotatable operating element, a thermal element adapted upon expansion and contraction to rotate the operating element in opposite directions, a pivoted member, an electric circuit closer mounted upon said member, a plurality of engaging members mounted on the operating element adapted to engage one of such members with one end of the pivoted circuit closer carrying member and upon rotation of the operating element to turn it about its pivot to open or close the circuit through the circuit closer, and upon further rotation in the same direction to move such member out of engagement but maintain the circuit closer in the same position, and means normally maintaining the end of the pivoted member in engagement with the operating member.

5. In a thermostatic controlled electric switch, a rotatable operating element, a thermal element adapted upon expansion and contraction to rotate the operating element in opposite directions, a pivoted member, an electric circuit closer mounted upon said member, a plurality of engaging members mounted on the operating element including a toothed wheel adapted to engage one of the teeth thereof with one end of the pivoted circuit closer carrying member and upon rotation of the operating element to turn it about its pivot to open or close the circuit through the circuit closer, and upon further rotation in the same direction to move such tooth out of engagement and wipe the following teeth thereover to maintain the pivoted member in the turned position.

6. In a thermostatic controlled electric switch, a rotatable operating element, a thermal element adapted upon expansion and contraction to rotate the operating element in opposite directions, a pivoted member, an electric circuit closer mounted upon said member, a plurality of engaging members mounted on the operating element adapted to engage one of such members with one end of the pivoted circuit closer carrying member and upon rotation of the operating element to turn it about its pivot to open or close the circuit through the circuit closer, and upon further rotation in the same direction to move such member out of engagement but maintain the circuit closer in the same position, and means normally maintaining the end of 130

the pivoted member in engagement with the engaging members of the operating member.

7. In a thermostatic controlled electric switch, a rotatable operating element, a thermal element adapted upon expansion and contraction to rotate the operating element in opposite directions, a pivoted member, an electric circuit closer mounted upon said member, a plurality of engaging members mounted on the operating element adapted to engage one of such members with one end of the pivoted circuit closer carrying member and upon rotation of the operating element to turn it about its pivot to open or close the circuit through the circuit closer, and upon further rotation in the same direction to move such member out of engagement but maintain the circuit closer in the same position, and means normally maintaining the end of the pivoted member in engagement with the operating member, and additional means to exert a return movement of the pivoted member to a normal vertical position.

8. In a thermostatic controlled electric switch, a circular rotatable operating element, a thermal element adapted upon expansion and contraction to rotate the operating element in opposite directions, a pivoted member, an electric circuit closer mounted upon said member, a plurality of engaging members including spaced apart teeth mounted on the operating element adapted to engage between two adjacent teeth one end of the pivoted circuit closer carrying member and upon rotation of the operating element to turn it about its pivot to open or close the circuit through the circuit closer and upon further rotation in the same direction to move the engaged tooth out of engagement but maintain the circuit closer in the same position by bringing into engagement the succeeding teeth and adapted upon rotation in the opposite direction to immediately engage between two adjacent teeth and return the circuit closer to the first position.

9. In a thermostatic controlled electric switch, a circular rotatable operating element, a thermal element adapted upon expansion and contraction to rotate the operating element in opposite directions, a pivoted member, an electric circuit closer mounted upon said member, a plurality of engaging members including spaced apart teeth mounted on the operating element adapted to engage one of such members with one end of the pivoted circuit closer carrying member and upon rotation of the operating element to turn it about its pivot to open or close the circuit through the circuit closer, and upon further rotation in the same direction to move the engaged tooth out of engagement but maintain the circuit closer in the same position by bringing into engagement the succeeding teeth and adapted upon rotation in the opposite direction to immediately engage between two adjacent teeth and return the circuit closer to the first position.

gage between two adjacent teeth and return the circuit closer to the first position.

10. In a thermostatic controlled electric switch, a circular rotatable operating element, a thermal element adapted upon expansion and contraction to rotate the operating element in opposite directions, a pivoted member, an electric circuit closer mounted upon said member, a plurality of spaced apart teeth mounted on the operating element adapted to engage one of such teeth with one end of the pivoted circuit closer carrying member and upon rotation of the operating element to turn it about its pivot to open or close the circuit through the circuit closer, and upon further rotation in the same direction to move the engaged tooth out of engagement but maintain the circuit closer in the same position by bringing into engagement the succeeding teeth, and adapted upon rotation in the opposite direction to immediately engage between two adjacent teeth and return the circuit closer to the first position.

11. In a thermostatic controlled electric switch, a circular rotatable operating element, a thermal element adapted upon expansion and contraction to rotate the operating element in opposite directions, a pivoted member, an electric circuit closer mounted upon said member, a plurality of spaced apart teeth mounted on the operating element adapted to engage one tooth with one end of the pivoted circuit closer carrying member and upon rotation of the operating element to turn it about its pivot to open or close the circuit through the circuit closer, and upon further rotation in the same direction to move the engaged tooth out of engagement but maintain the circuit closer in the same position by bringing into engagement the succeeding teeth, and means normally maintaining the end of the pivoted member in engagement with the operating member and adapted upon rotation in the opposite direction to immediately engage between adjacent teeth and return the circuit closer to the first position.

12. In a thermostatic controlled electric switch, a rotatable operating element, a thermal element adapted upon expansion and contraction to rotate the operating element in opposite directions, a pivoted member, an electric circuit closer mounted upon said member, a plurality of engaging members mounted on the operating element including a toothed wheel adapted to engage one of the teeth thereof with one end of the pivoted circuit closer carrying member and upon rotation of the operating element to turn it about its pivot to open or close the circuit through the circuit closer, and upon further rotation in the same direction to move such tooth out of engagement and wipe the following teeth thereover to maintain the pivoted member in the turned position and adapted

- upon rotation in the opposite direction to immediately engage the end between adjacent teeth and return the circuit closer to the first position.
- 5 13. In a thermostatic controlled electric switch, a rotatable operating element, a thermal element adapted upon expansion and contraction to rotate the operating element in opposite directions, a pivoted member, an electric circuit closer mounted upon said member, a plurality of radial teeth mounted on the operating element adapted to engage one of such teeth with one end of the pivoted circuit closer carrying member and upon rotation of the operating element to turn it about its pivot to open or close the circuit through the circuit closer, and upon further rotation in the same direction to move such tooth out of engagement but maintain the circuit closer in the same position by wiping the succeeding teeth thereover and means normally maintaining the end of the pivoted member in engagement with the engaging members of the operating member, and adapted upon rotation in the opposite direction to immediate engage between adjacent teeth and return the circuit closer to the first position.
- 10 14. In a thermostatic controlled electric switch, a rotatable operating element, a thermal element adapted upon expansion and contraction to rotate the operating element in opposite directions, a pivoted member, an electric circuit closer mounted upon said member, a plurality of radial teeth mounted on the operating element adapted to engage one of such teeth with one end of the pivoted circuit closer carrying member and upon rotation of the operating element to turn it about its pivot to open or close the circuit through the circuit closer, and upon further rotation in the same direction to move such tooth out of engagement but maintain the circuit closer in the same position by wiping succeeding teeth over the end thereof, and means normally maintaining the end of the pivoted member in engagement with the operating member, and additional means to exert a return movement of the pivoted member to a normal vertical position and adapted upon rotation in the opposite direction to immediately engage the end between adjacent teeth and return the circuit closer to the first position.
- 15 15. In a thermostatic controlled electric switch, a rotatable toothed disc, a thermal element adapted upon expansion and contraction to rotate the disc in opposite directions, a switch operating arm mounted therebelow, having a free end adapted to enter between adjacent disc teeth when in line with the centers of the disc and arm mounting, electric

switch contacts, means coacting with the operating arm to open and close said contacts, the rotation of the disc in one direction moving the free end of the arm to close said contacts, and rotation of the disc in the opposite direction engages the adjacent disc teeth to move the free end of the arm in the opposite direction to open said contacts.

20 16. In a thermostatic controlled electric switch, a rotatable toothed disc, a thermal element adapted upon expansion and contraction to rotate the disc in opposite directions, a switch operating arm mounted therebelow, having a free end adapted to enter between adjacent disc teeth when in line with the centers of the disc and arm mounting, electric switch contacts, means coacting with the operating arm to open and close said contacts, the rotation of the disc in one direction moving the free end of the arm to close said contacts, continued movement in the same direction passing the engaging disc teeth over the free end of the arm and engaging the succeeding following teeth therewith to maintain the contacts closed, and rotation of the disc in the opposite direction engages the adjacent disc teeth to move the free end of the arm in the opposite direction to open said contacts.

25 17. In a thermostatic controlled electric switch, a rotatable toothed disc, a thermal element adapted upon expansion and contraction to rotate the disc in opposite directions, a switch operating arm mounted therebelow, having a free end adapted to enter between adjacent disc teeth when in line with the centers of the disc and arm mounting, electric switch contacts, means coacting with the operating arm to open and close said contacts, the rotation of the disc in one direction moving the free end of the arm to close said contacts, rotation of the disc in the opposite direction engages the adjacent disc teeth to move the free end of the arm in the opposite direction to open said contacts, and means exerting a return movement of the arm.

30 18. In a thermostatic controlled electric switch, a rotatable toothed disc, a thermal element adapted upon expansion and contraction to rotate the disc in opposite directions, a switch operating arm mounted therebelow, having a free end adapted to enter between adjacent disc teeth when in line with the centers of the disc and arm mounting, electric switch contacts, means coacting with the operating arm to open and close said contacts, the rotation of the disc in one direction moving the free end of the arm to close said contacts, continued movement in the same direction passing the engaging disc teeth over the free end of the arm and engaging the succeeding following teeth therewith
